(57) CLAIM

The ornamental design for a combined perfume holder and pendant, as shown and described.

DESCRIPTION

FIG. 1 is a perspective view of a combined perfume holder and pendant showing my new design;

FIG. 2 is a front elevation view thereof;

FIG. 3 is a rear elevation view thereof;

FIG. 4 is a side elevation view thereof;

FIG. 5 is an opposite side elevation view thereof;

FIG. 6 is a top plan view thereof;

FIG. 7 is a bottom plan view thereof; and,

FIG. 8 is another perspective view thereof, showing the combined perfume holder and pendant of FIG. 1 in an alternate configuration of use.

The broken lines in the drawings represent portions of the combined perfume holder and pendant that form no part of the claimed design.
